UNITED STATES PATENT OFFICE

2,516,443

COUNTING AND RECORDING APPARATUS

Reginald R. S. Wylde, Miami, Fla.

Application July 17, 1946, Serial No. 684,164

5 Claims. (Cl. 346—14)

1

The invention relates to apparatus for counting series of objects, and for purposes of disclosure an embodiment thereof has been illustrated in the accompanying drawings, and will be hereinafter described, which has been designed primarily for use in laundries and the like for counting and making a printed record of the total of the pieces of laundry in a batch. However, it will be readily apparent to those skilled in the art that the principles involved in the apparatus are by no means limited to such specific application, but may be advantageously employed in the counting and registering or recording of numerous other articles or objects.

One of the purposes of the invention is to provide a relatively small and compact machine, which may be readily moved from place to place to position it in co-operative relation to chutes or the like adapted to receive the articles after they have been counted and transfer them to other locations for further operations; or if desired the machine may be anchored at one location and discharge the counted articles, either onto a belt or like conveyor passing beneath the discharge opening, or directly into portable trucks, baskets or the like positioned beneath such opening.

A further object of the invention is to provide an apparatus of the character described wherein the articles to be counted are serially passed between a source of light and a photoelectric cell or equivalent light-responsive device, which device controls the actuating elements of the counting mechanism whereby the indicia-bearing members of the latter will be advanced step by step with each interruption of the light beam due to passage of the articles between the light source and light-responsive device. The counting mechanism may be merely a visual indicator or register, but preferably it comprises a recorder adapted to print the total number of articles in a batch upon a card or sheet presented to the recorder.

A still further object of the invention is to provide an article counting and recording apparatus wherein the recording mechanism is provided with a slide for receiving a card or sheet upon which the record is to be made, said slide being movable to and from a position in which a portion of the card or sheet is juxtaposed to the indicia-bearing members of the counter, and in which the movement of the slide to such position serves to retract and release a printing hammer, which thereby strikes the card and presses it against the counter indicia whereby an impres-

2

sion of the latter is transferred to the card. The return movement of the slide may be conveniently employed to clear the counter, i. e. return its indicia-bearing members to their zero positions preparatory to the beginning of a new count; and the recorder preferably includes a traveling inked ribbon passing across the face of the indicia, against which the surface of the card is pressed by the printing hammer to produce the impression on the card. The ribbon travels from one spool to another in step by step movements induced by the means which advances the indicia-bearing members of the counter, and the direction of travel of the ribbon is automatically reversed as each spool becomes empty, through an increase in tension on the ribbon.

Other more or less secondary objects will appear as the description proceeds.

In the accompanying drawings forming a part of this specification:

Fig. 1 is a side elevational view of a machine embodying the principles of the invention, and designed primarily for the counting of towels, linens and other pieces of laundry;

Fig. 2 is an end elevational view of such machine, as seen from the right of Fig. 1;

Fig. 3 is an enlarged side elevational view of the counting and recording mechanism, the parts being shown in the positions they normally occupy;

Fig. 4 is a view similar to Fig. 3 but looking from the opposite side, portions of the parts being broken away and in section;

Fig. 5 is an end elevational view of the mechanism shown in Fig. 3, as seen from the right thereof;

Fig. 6 is a similar view, looking from the left of Fig. 3;

Fig. 7 is a plan view, looking down on Fig. 3;

Fig. 8 is a fragmentary view similar to Fig. 3 but partly in section, and illustrating positions assumed by the parts in the course of a printing operation;

Fig. 8^a is a perspective view of a portion of the lever and the pivoted dog carried thereby, which actuate the printing hammer;

Fig. 9 is a plan view, partly broken away and in section, of the counter unit per se;

Fig. 10 is a longitudinal sectional view on approximately the plane indicated by the line 10—10 of Fig. 9, looking in the direction of the arrows; and

Figs. 11, 12, 13 and 14 are cross sectional views on the respective planes indicated by the several

lines 11—11, 12—12, 13—13 and 14—14 of Fig. 10, looking in the directions of the arrows.

Referring first more particularly to Figs. 1 and 2, the machine comprises an open framework 21, conveniently formed of metal tubing, and the four legs of which are provided at their lower ends with rollers or casters 22 on which the machine may be easily rolled over the floor. One of the legs is preferably provided with a brake or stop device comprising a vertically slideable member 23, operable by a cammed lever 24 to engage and disengage its foot with the floor surface, whereby the machine may be anchored against movement at any desired location.

As will be readily understood from the drawings, the lower portions of the frame legs are so spaced as to accommodate a transporting device such as a belt conveyer, or as here shown, a laundry truck or receptacle 25, disposed between them to receive the counted articles; or the machine may be positioned over a chute or other opening in the floor, through which the articles may pass to other stations. The upper portions of the frame legs converge and support the throat portion 26 of a flared chute or hopper 27 into the open upper portion 28 of which the articles are serially introduced in any appropriate manner.

A housing 29 mounted at one side of the throat 26 encloses an electric lamp or other suitable source of light 30, while at the opposite side of the throat a housing 31 encloses a photoelectric cell or equivalent light-responsive device 32. The circuits of the light source and the light-responsive device are purely conventional and so have not been illustrated in detail, but the wires thereof are enclosed in suitable conduits 33, one portion of which extends to the counting and recording mechanism 34 which is mounted on a bracket 35 carried by the frame 21. As will appear more fully below, certain portions of this mechanism are actuated by an electromagnet or solenoid 36, which is in circuit with and controlled by the light-responsive device 32.

The details of the counting and recording mechanism 34 are better illustrated in Figs. 3-14, to which reference is now made. As here shown this mechanism comprises an upright plate-like standard 37, having a rigid base plate 38 by means of which it may be mounted on the bracket 35, and a horizontal head plate 39 upon which is secured the counter unit 40. The details of this unit will be more fully described later, but for the present it may be said that it comprises an open topped rectangular casing 41 in which is journaled a longitudinally disposed shaft 42, on which is rotatably mounted a plurality of adjacent counting wheels 43 having raised numerical indicia 44 (see particularly Figs. 9-14). These wheels are arranged to be sequentially advanced, step-by-step, by an operating lever 45 which is connected by a link 46 to the armature or plunger 47 of the solenoid 36.

As best shown in Fig. 5, an inked ribbon 50 has one of its ends attached to the hub 51 of a spool 52, from which it extends downwardly to an idler roll 53, thence upwardly to an idler roll 54, then horizontally over the open top of the counter 40, in juxtaposition to the faces of the uppermost indicia of the several wheels 43, to an idler roll 55, thence downwardly to an idler roll 56 and finally upwardly to a spool 57, to the hub 58 of which the other end of the ribbon is attached. The respective spools 52 and 57 are removably mounted on the studs 59 and 60 carried by the standard 37, and have readily detachable driving

connections 61 and 62 (Figs. 3 and 4) with gears 63 and 64 which are journaled on the respective studs.

A spindle 65 passes through and is journaled in the standard 37, and at one end rigidly carries a gear 66 and adjacent its other end a ratchet wheel 67. An arm 68 is journaled on the spindle 65 adjacent said ratchet wheel and carries a spring pawl 69 co-operating with the latter; the said arm also being connected by suitable linkage 70 to the operating lever 45. A rock arm 71 is also journaled on the spindle 65, adjacent the gear 66, and carries a pair of studs 72 and 73 respectively journaling gears 74 and 75. This rock arm also mounts the ribbon idler rolls 53 and 56 previously referred to, as will be clear from Fig. 5. The rock arm 71 and the gears 66, 74 and 75 are so constructed and arranged that the gears 74 and 75 are in constant mesh with the gear 66, and by arcuate movement of the rock arm in one direction or the other the said gears 74 and 75 may be alternatively brought into meshing engagement with spool driving gears 63 and 64 respectively.

The mechanism just described constitutes an automatic ribbon feed and reversing device, the operation of which is as follows: As the operating arm 45 is oscillated by the solenoid 46, its motion will be transmitted through the linkage 70, ratchet arm 68, pawl 69, ratchet wheel 67, spindle 65 and gear 66 to the gears 74 and 75. These will thus be advanced in step by step movements which will be transmitted to which ever spool gear 63 or 64 happens to be engaged with such gears 74 or 75 at the time, thereby 35 rotating the spool associated with the engaged gear 63 or 64, and winding the ribbon thereon from the other spool, the gear of which is at that time disengaged. When these movements have completely unwound the ribbon from the free spool, since the ribbon end is attached to the hub of such spool, any additional movements will serve to increase the tension on the ribbon and by reason of the training of the latter about the idler rolls 53 and 56 carried by the rock arm 71, the latter will be shifted on the spindle 65 to disengage the previously engaged pair of spool driving gears, and to re-engage the previously disengaged pair; thus freeing the full spool and transferring the drive to the empty one.

In Fig. 5 the parts are illustrated as having just completed such a reversal, whereby the drive has been transferred from the full spool 52 to the empty spool 57. In the interests of clearness the arc of movement of the rock arm 71 has been somewhat exaggerated here, and in practice it need be only sufficient to insure complete disengagement of the teeth of the respective pairs of gears 63—74 and 64—75. To retain the parts in each position of gear engagement, there is provided a spring pressed detent 76 housed in a barrel 77 carried by the standard 37 carried by the standard 37, the point of which detent is alternatively engageable in notches 78 and 79 provided in a sector 80 formed as a part of the rock arm 71. Before yielding in the course of a reverse, this detent enables the placing of sufficient tension on the ribbon to cause the shift of the rock arm to be effected with a snap action which insures the engagement of the new pair of spool driving gears, as will be readily understood.

Secured to and extending from one side of the counter casing 41 is a pair of spaced bracket arms 81 provided with suitable guideways 82 in which a slide 83 is mounted for manually induced reciprocating movements. The slide is of appro-

priate dimensions to receive and support a card or sheet 84 (Figs. 4 and 8) on which the indications of the counter 40 are to be printed, and at its outer end the slide is provided with a grip or finger piece 85, while its inner portion is apertured to provide a window 86. The normal position of the slide is that illustrated in Figs. 3, 4 and 7, but when it is pushed inwardly (as indicated in Fig. 8) the window 86 will be brought to a position above the counter wheels 43 in which an impression of the uppermost indicia of such wheels may be secured on the under surface of the card, through the said window.

Rigidly attached to the slide 83, as by a bracket member 87, is a rack bar 88 the teeth of which engage with those of a pinion 89 carried by the shaft 42 of the counter 40, for a purpose to be later described. The end of the rack bar carries a member 90 provided with a pin 91 which works in an inclined slot 92 formed in the upper portion of a vertically disposed lever 93 which is pivotally mounted at 94 in ears 95 carried by the standard 37. The lower end of the lever 93 is provided with an angular extension 96, while the upper end of said lever is provided with an oppositely disposed angular extension 97 to which a dog 98 is pivotally connected as at 99, and the downward movement of which is limited by a pin 100 carried by said lever extension 97.

Extending from the counter casing 41 in a direction opposite to that of the arms 81 is a second pair of bracket arms 101 which mount a printing hammer structure 102. This structure comprises a pair of spaced arms 103 and 104 the outer ends of which are pivotally secured as at 105 to the bracket arms 101, while the inner ends of the said hammer arms are connected by a bridge piece 106 the under face of which carries a rubber, felt or like yieldable pad 107. The hammer arm 103 carries a stud or roller 108 projecting into the path of travel of the dog 98; and a tension spring 109 has one of its ends anchored to the arm 103 and its other end adjustably anchored to the angular extension 96 of the lever 93, whereby it serves to normally retain such lever, the hammer 102 and the slide 83 in the positions shown in Figs. 3-7.

The operation of the printing mechanism just described is as follows: At the conclusion of a count, when it is desired to secure a printed record of the indication of the counter 40, a card or sheet 84 is placed in the slide 83 and the latter is manually pushed toward the left, as viewed in Figs. 3 and 7, to bring the window 86 of the slide into register with the counter wheels 43. Such movement of the slide will be transmitted through the bracket 87, rack bar 88, connecting member 90, and pin and slot connection 91, 92 to the lever 93, which will thus be swung to the left, as indicated in Fig. 8, against the tension of spring 109. Such movement of the lever 93 will cause the dog 98 to engage the roller 108 and lift the hammer 102, also against the action of spring 109. As the window 86 of slide 83 reaches its position of registration with the counter wheels 43, the lever 93 completes its movement—from the full line to the broken line position shown in Fig. 8—thereby moving the dog 98 beyond the roller 108, whereupon the spring 109 snaps the hammer 102 back to its initial position, causing the pad 107 to press the under surface of the card 84 against the ribbon 50 and it in turn against the faces of the uppermost indicia of the counter wheels 43, thereby transferring an impression of such indicia to the card surface. If the operator now releases

the slide 83, the spring 109 will restore the lever 93, rack 88 and slide 83 to their normal positions, during which movements the dog 98 will ride over the roller 108 until it clears the same and then drop back to its position in engagement with the pin 100. As this action is quite rapid, a stop pin 116 is preferably provided on the hammer arm 103 to prevent the dog from being thrown over to an inoperative position.

10 The counting device 40 may be of any appropriate type, but preferably takes the form shown in detail in Figs. 9-14. As above indicated, the shaft 42 thereof extends longitudinally of the casing 41 and has the indicia-bearing wheels 43 journaled upon it. The units wheel—the one furthest to the left in Figs. 9 and 10—has a ratchet wheel 111 secured to it which ratchet is arranged to be advanced step by step by a pawl 112 pivotally carried by a slidable block 113 mounted for reciprocation in guides 114 carried by the bottom plate 115 of the counter casing 41. As best shown in Fig. 13, the block 113 is urged to a retracted position by a compression spring 116, and the said block also carries an upright finger 117 which, in said retracted position, engages the teeth of the ratchet wheel 111 to prevent retrograde movement of the latter.

To advance the ratchet one step the block 113 is moved toward the left, as viewed in Fig. 13, by means of a pin 118 carried by an oscillatory arm 119 and engageable with the said finger 117. The arm 119 is rigid with a thimble 120 journaled in the end wall of casing 41 and bored to receive and journal an end portion of the shaft 42, see Fig. 9. The thimble is provided with a stud 121 to which the operating arm 45 is rigidly attached, and thus with each movement of such arm by the solenoid 36 the block 113 will be moved, against the pressure of spring 116, to the position shown in Fig. 14, and the ratchet wheel 111 and units wheel 43 advanced one step. Upon de-energization of the solenoid the spring 116 will return the parts to the Fig. 13 position, with the finger 117 moving into engagement with the ratchet to prevent backward movement thereof.

To transmit motion thus imparted to the units wheel 43 to the succeeding counter wheels to advance them from time to time as a preceding wheel completes a revolution, a gear transfer mechanism is provided. That is to say, each of the counter wheels 43, except the units wheel, has a gear 122 secured to it in axially spaced relation, with each of which gears meshes a pinion 123 journaled on a longitudinal rod 124. Each of the said pinions carries a shroud 125 which is received in the groove or space between its associated gear 122 and companion counter wheel 43, whereby longitudinal movement of the pinions on the rod 124 will be prevented. As will be clear from Fig. 9, each pinion 123 is wider than the gear 122 with which it meshes, so as to extend into the path of a small patch gear 126 carried by the preceding counter wheel 43. The parts are so proportioned and arranged that each patch gear 126 engages, moves, and disengages its mating pinion in the course of one-tenth of a revolution of the counter wheel carrying such patch gear, which engagement and movement take place as such counter wheel is being advanced from its "9" to its "0" indication. The pinion 123 of course transmits the movement to the gear 122 of the succeeding counter wheel, which is thus advanced one-tenth of a revolution. A comb spring 127 is secured to a side wall of the casing 75 41 and its teeth 128 yieldably engage the teeth

of the several gears 122 to prevent unintentional movements of the said gears and their associated counter wheels 43. The said spring replaces the usual "Geneva lock," and secures and maintains exact alinement of the counter wheel indicia.

For clearing the counter, i. e. resetting its several wheels 43 to their zero positions preparatory to starting a new count, the shaft 42 is provided with a longitudinal notch 129 and the bore of each wheel is provided with a recess 130 (Fig. 12) in which is seated a V-shaped spring pawl 131 the inner leg of which will enter the notch when the latter is alined with the recess. The shaft 42 is normally stationary and the wheels 43 journal thereon in their advancing movements, which take place in a clockwise direction as viewed in Fig. 12; and as each wheel advances the inner leg of its spring pawl 131 will be forced outwardly into the recess 130 by the shaft periphery.

When the slide 83 is advanced from its normal position, as in Fig. 8, its movement will be transmitted through the rack 88 and pinion 89 to the shaft 42, which will thus be moved in a counter-clockwise direction, as viewed in Fig. 12. However, when the slide is released and returned to its normal position by the spring 109, the direction of rotation of the shaft 42 will be reversed, and as its notch 129 alines with the recesses 130 of the respective wheels 43, the inner legs of the pawls 131 thereof will enter the notch and the wheels will thus be picked up and rotated with the shaft back to their zero positions.

It will be readily understood from the foregoing that with the serial feeding of objects, such for example as pieces of laundry, into the chute 27 they will pass downwardly through the throat 26 to the receptacle, conveyer or chute beneath the latter. As each piece passes between the light source 30 and the light-responsive device 32 the latter will cause an energization of the solenoid 36 which will advance the counter one step. When all of the objects have been thus passed through the machine, a card or sheet 84 is placed in the slide 83 and the latter pushed in and then released. The inward movement of the slide will cause actuation of the printing hammer 102 whereby a printed record of the counter indication will be made on the card or sheet; and the return movement of the slide will clear or reset the counter for the beginning of a new count at zero. In the meantime, with each actuation of the solenoid the inked printing ribbon 58 will be slightly advanced, and when it reaches the limit of its travel, its direction of motion will be automatically reversed.

What is claimed is:

1. In apparatus for counting and recording the total of a series of objects, the combination of a light source; a light-responsive control device spaced therefrom; means for conducting the objects between said source and device to intermittently actuate the latter; counter mechanism having indicia-carrying wheels; means controlled by said light-responsive device for advancing the counter wheels step-by-step in response to the intermittent actuations of said device; a manually movable card-receiving member mounted adjacent the counter wheels for receiving and carrying individual record cards to and from a printing position relative to the wheels; a printing member mounted for movement toward and from the wheel indicia; and motion transmitting connections between said card-receiving and printing members whereby movements of the former will actuate the latter to press a card advanced to the

printing position against the wheel indicia and record an impression thereof upon the card.

2. In apparatus for counting and recording the total of a series of objects, the combination of a light source; a light-responsive device spaced therefrom; means for conducting the objects between said source and device to produce intermittent actuation of the latter; counter mechanism having indicia-carrying wheels; means controlled by said light-responsive device for advancing the counter wheels step-by-step in response to the intermittent actuations of said device; a card-receiving member mounted for movement adjacent the counter wheels whereby to carry individual record cards to and from a printing position relative to said wheels, said member being manually movable to said position; a printing member mounted for movement toward and from the wheel indicia; motion transmitting elements connected to and movable by the card-receiving member, and having portions transiently engageable with the printing member to retract it from the counter wheels as the card-receiving member is manually moved to advance a card to said printing position; and spring means connected to said printing member and motion transmitting connections, for returning the printing member toward said wheels upon release of said transiently engageable portions to press the advanced card against the wheel indicia to record an impression thereof upon the card, said spring means also moving said card-carrying member and card from said printing position upon discontinuance of the manual pressure upon said member.

3. In apparatus for counting and recording the total of a series of objects, the combination of a light source; a light-responsive control device spaced therefrom; means for conducting the objects between said source and device to produce intermittent actuation of the latter; counter mechanism having indicia-carrying wheels; means controlled by said light-responsive device for advancing the counter wheels step-by-step in response to the intermittent actuations of said device; a manually operable card-receiving member mounted adjacent the counter wheels for movements to advance individual record cards deposited on the member to a printing position relative to said wheels, and to retract the cards from said position; a printing member mounted for movement toward and from the wheel indicia; a lever connected to and swingable by the card-receiving member; a dog carried by said lever and transiently engageable with the printing member during movement of the card-receiving member toward its said printing position, whereby to retract the printing member from the counter wheels and then release it; and a spring connected to said lever and printing member for returning the latter toward the counter wheels to press the advanced card against their indicia to record an impression thereof upon the card, said spring also acting upon the lever to return the card-carrying member and card from said printing position upon release of the manual pressure on said member.

4. In apparatus for counting and recording the total of a series of objects, the combination of a light source; a light-responsive control device spaced therefrom; means for conducting the objects between said source and device to produce intermittent actuation of the latter; counter mechanism having indicia-carrying wheels; means controlled by said light-responsive device for advancing the counter wheels step-by-step in

response to the intermittent actuations of said device; a manually operable card-receiving member slidably mounted adjacent the counter wheels for reciprocating movements whereby to advance and retract individual record cards deposited on said member to and from a printing position relative to the wheels; a printing member pivotally mounted for swinging movements toward and from the wheel indicia; a lever connected to and swingable by the card-receiving member; a dog carried by said lever and transiently engageable with the printing member during movement of the card-receiving member toward said printing position, whereby to withdraw the printing member from the counter wheel indicia, and then release it; and a spring having one end connected to said lever and its other end connected to the printing member, for returning the latter toward the counter wheels to press the advanced card against their indicia to record an impression thereof upon the card, said spring also acting upon the lever to return the card-receiving member and card from said printing position upon release of the manual pressure on said member.

5. In apparatus for counting and recording the total of a series of objects passing between a source of light and a light-responsive control device spaced therefrom, the combination of a counter mechanism having indicia-carrying wheels; means controlled by the light-responsive device for advancing the counter wheels step-by-step in accordance with the intermittent actuations of said device; a manually operable slide member reciprocatably mounted adjacent the counter wheels, for receiving and advancing a record card to a printing position relative to the

wheels, and retracting it therefrom; a printing member mounted for movements toward and from the wheel indicia; a spring connected to and biasing the printing member toward the wheels; motion transmitting connections between said slide and printing member, including a rack and transiently engageable elements the latter of which being operable as the slide advances a card to the printing position to retract the printing member from the wheels and then to release it whereby the spring may return said member toward the wheels to press the advanced card against the wheel indicia to record an impression thereon upon the card; and mechanism including a pinion engaging said rack and operable thereby as the slide retracts the printed card to restore the counter wheels to their zero positions.
